TAG PRINTING AND STAPLING MACHINE

Albert F. Horton, Cranston, R. I., assignor to
 Boston Wire Stitcher Company, Portland,
 Maine, a corporation of Maine

Application November 2, 1928, Serial No. 316,836

19 Claims. (Cl. 93—88)

This invention relates to an automatic tag-printing and -affixing machine for printing price-tags, tickets, labels and the like and simultaneously attaching the same to hosiery, garments or other articles of commerce.

One object of the invention is to provide a machine for feeding price-tags, tickets, labels and the like in strip form and simultaneously printing a tag, severing it from the strip, and stitching it to the work.

Another object of the invention is to provide an automatic tag-printing and -affixing machine wherein the tags or the like are fed through the machine and printed with price symbols or other indicia by means actuated by or from the stapling-mechanism.

Another object of the invention is to provide an automatic tag-affixing machine wherein the tags, or the like, are fed through the machine in strip form and individually detached from the strip by severing means actuated by or from the stapling-mechanism.

Another object of the invention is to provide an automatic machine of the type specified, which is simple in construction, efficient in operation and economical to manufacture.

Further objects of the improvement are set forth in the following specification which describes a preferred form of construction of the invention, by way of example only, as illustrated by the accompanying drawings. In the drawings:

Fig. 1 is a part-sectional side elevation of the improved tag-printing and -affixing machine shown as embodied in a preferred form of construction;

Fig. 2 is an enlarged front elevation of the machine showing the stapling-head lowered against the work;

Fig. 3 is a view similar to Fig. 2 showing the parts in position near the completion of the stapling operation;

Fig. 4 is a fragmentary view of the front of the machine, showing the stapling-head raised and the ink pad positioned against the printing type;

Fig. 5 is a plan view of the machine;

Fig. 6 is a plan view of the base of the machine showing the strip of tags and the feeding-mechanism therefor;

Fig. 7 is a longitudinal sectional view of the machine taken on line 7—7 of Fig. 2;

Fig. 8 is a plan view of the rear portion of the machine, showing the means for supporting the tag-strip spool or roll; and

Fig. 9 is a perspective view showing a portion of the tag-strip.

The invention is herein illustrated and described as embodied in a hand-operated machine adapted to affix price tags to hosiery, underwear and other articles of commerce, but it is to be understood that certain or all of its features may be applied to use with machines of other types; and that in lieu of price-tags, other devices such as tickets, labels and the like in strip or other form may also be used without departing from the scope of the invention. For the sake of brevity, however, the strip to be fed and printed in the machine will be hereinafter referred to as comprising tags.

In general, the improved machine comprises a base or standard having a stapling-arm hinged thereto. The stapling-arm is constructed to provide a magazine for holding a supply of staples and at its outer end is a head carrying the stapling- or stitching-mechanism for affixing the tags to the work. The head also carries means for printing suitable price symbols or other indicia on the tags as they are affixed to the work. Preferably, the tags used with the machine are in strip form, the strip being rolled or coiled on a spool rotatively mounted at the rear of the base of the machine. To provide that the tags may be readily detached from the strip, the latter is perforated or slotted laterally at uniform intervals and the stapling-head carries cutters for parting the un-slotted portion of the strip to sever the tag therefrom during the stapling operation. For holding the work in position in affixing a tag thereto, the base is provided at its forward end with a platen, and preferably the platen or work-support carries means for clinching or bending over the legs of the staples after the latter have been driven through the tag and the work.

The machine is preferably so constituted that during its operation the initial downward movement of the stapling-arm causes the strip of tags to be fed forwardly the required distance to position the foremost tag over the work held on the platen, whereupon it is printed and stapled or stitched to the work. The stapling-head is provided with a spring-pressed plunger which may carry the type for printing the indicia on the tag as well as the staple-driving means, and also the tag-severing means. When the stapling-arm has reached the limit of its downward movement the continued pressure applied against the top of the plunger causes it to descend, and during this action three operations are performed simultaneously: a staple from the magazine on the

arm is carried downwardly and its legs driven through the tag and the work and clinched against the underside thereof; the faces of the type are impressed upon the tag; and the tag 5 severed or detached from the strip. When the plunger reaches the limit of its downward stroke the pressure of the hand is removed and both the plunger and the arm are returned to raised position through the action of springs or other suitable 10 instrumentalities as provided for this purpose. The work is then removed from the platen and a new piece inserted, whereupon the operation is repeated.

Referring to the drawings, the improved machine as herein illustrated comprises a base 11 designed to rest on a table, bench or other support and preferably provided with cushioned feet 24. Hingedly mounted on the base 11 is the stapling-arm 13 carrying the head 12 which is adapted to 15 be pressed down against the work placed on the platen 14 at the forward end of the base. The base 11 also supports a bifurcated frame 15 for carrying the roll or spool of tags T in strip form. The arm 13 is constructed to serve as a magazine for holding a supply of wire staples s, and mounted within the base beneath the arm are 20 means for feeding the strip of tags T forwardly a predetermined distance when the stapling-head is depressed.

The base 11 is preferably formed of a pair of 25 similarly-shaped sheet-metal side-plates 16 held in spaced relation by a plurality of cylindrical struts 17 arranged at intervals to provide a rigid structure. The ends of the struts 17 have 30 threaded holes for receiving the shanks of screws 18 passing through openings in the plates 16 and set up thereagainst to clamp the parts in place. Adjacent their forward ends the plates 16 are cut 35 away or notched at 19 with the metal at the sides of the notches folded or bent to provide, respectively, inwardly projecting vertical fingers 20, and inwardly extending horizontal flanges 21. The fingers 20 are disposed beneath the rear of 40 the head 12, while the horizontal flanges 21 constitute means for supporting the platen 14 which 45 is secured thereto by screws 22, or other suitable fastening means, see Figs. 1, 2 and 3. At the lower corners of the side-plates 16 are angular strips 50 of sheet-metal 23, made integral therewith or fastened thereto, the horizontal portions of which carry the feed or pads 24. Elongated openings 25 are formed in the rear portion of the plates 16 to save weight and permit access to the interior 55 of the base for convenience in inserting or adjusting the strip of tags T.

The stapling-arm 13 may be constructed in the form of a flat-sided bar of suitable width to adapt the staples s to be straddled across its top. On the under side of the arm 13 is a hinge-member 27, preferably formed from sheet-metal and secured to the arm by means of screws 28 shown in Fig. 7. The member 27 constitutes the means by which the arm 13 is pivotally mounted on the base 11, one end of the hinge-member 60 being provided with depending perforated ears 29 through which extends a bolt or pin 30 secured fast in the side-plates 16, see Fig. 6. To hold the arm 13 laterally with respect to the base 11, the sides of the hinge-member 27 extending rearwardly from the ears 29 are provided with upwardly bent wings or flanges 31 abutting the sides of the arm, see Figs. 1 and 7.

The stapling-arm 13 is normally maintained in raised position, as shown in Fig. 1, by means 75 of a coil spring 32 located at the rearward end

of the base 11. One end of the spring 32 is secured to a pin 33 projecting from one of the side-plates 16, while its opposite end is attached to the extremity of a tail-piece or finger 34 fastened to the bottom of the arm by means of a screw 26. The upward swinging movement of the arm 13 is limited by an angularly disposed saddle 35 extending between the side-plates 16 of the base 11 beneath the rearward portion of the arm. The saddle 35 is preferably constructed 10 from sheet-metal bent into U-shape, as shown in Figs. 5, 6 and 7, and fastened to the plates 16 by screws, rivets or other suitable means.

The stapling-head 12 comprises opposite vertical side-plates 36 fastened to the sides of the arm 13. The plates 36 extend upwardly above the top of the arm 13 to form a hollow casing and are rounded off on their rearward edges. Abutting the inner faces of the plates 36 are thinner lining-plates 37 secured in place by means 20 as later described. The lining-plates 37 have their lower edges spaced slightly above the top of the arm 13 to provide a channel for the upper cross-bars of the staples s, see Fig. 7, and the outer plates 36 are recessed adjacent the 25 sides of the arm to permit the legs of the staples to readily slide therealong. The forward portions of the lining-plates 37 are cut away except at the bottom, where the metal is slotted to form pointed prongs 39 bent inwardly to provide 30 a rest for supporting the lower end of a coil spring 40 which operates the stapling-plunger er in the manner as later explained.

The lining-plates 37 are held in position abutting the inner faces of the plates 36 by spacers 35 41 and 42. The upper spacer 41 has a hexagonal body, the ends of which are bored and threaded to receive the shanks of screws 43 projecting through holes in the plates. The lower spacer 42 is constructed in the form of a stud 40 having an enlarged central portion arranged with its shoulders abutting the inner faces of the lining-plates 37 and its reduced ends inserted through holes in the outer plates 36. The spacer 42 is employed as a guide for a spring 44 which 45 operates a staple-pusher 45 to be next described.

The staple-pusher 45 consists of a sheet-metal slide of inverted U-shape, arranged with its sides straddling the top of the arm 13 as shown in Fig. 7. The rearward end of the staple-pusher 50 50 is provided with a tail-piece 46 having a hook 47 engaged through an opening in the bottom of a curved finger-loop 48. The forward end of the finger-loop 48 is slotted to adapt it to receive the end of the flat ribbon-like spring 44, 55 which is looped through the slits to secure it thereto. The forward end of the spring 44 is wound into a convolute coil with its inner end secured to a cross-member 50 held between the inner side-plates 37. From the coil the spring 44 extends down under the spacer 42, and reaching back to the pusher 45 tends to slide the latter on the arm 13 to feed the staples forward to deliver them individually under the staple-driver in the manner as later more fully explained. 65

A staple-guard 51, constructed from an angularly folded sheet-metal strip, is welded to one side of the arm 13, see Fig. 5, with its upper part overlying the top of the arm in spaced relation with respect thereto as shown in Fig. 7. The staples s slide in the space between the overhanging guard 51 and the top of the arm 13 and are thereby restrained from rising up on the arm. 70

The stapling-mechanism is operated from a reciprocating plunger 52 constructed in the form 75

of a hollow or part-tubular shell which may be struck-up from sheet-metal. The opposite sides of the plunger 52 straddle the forward sides of the head 12 and are bent inwardly to provide 5 runners 53, see Fig. 1, which slide in vertical grooves 54 formed in the outer faces of the plates 36. At the top of the plunger 52 is a knob or presser 55 having its hub 56 fitted within the sides of the plunger and fastened in place by a 10 screw 57 reaching through from the front. A pin 58 projects downwardly from the hub 56 and passes through the upper coils of the spring 40 which, as before explained, has its lower end resting on the prongs 39. The spring 40, as will be 15 observed by reference to Fig. 7, acts to raise the plunger 52 to its uppermost position, and to return it to this position after each stroke is made to apply a staple to the work.

The staple-driver is of usual form, being constructed as a flat blade 59 shouldered on its lateral edges to provide narrow splines 60 which slide in vertical grooves or guideways 61 formed on the inner faces of the side-plates 36. The 20 staple-driver 59 is held in parallel spaced relation with respect to the forward wall of the plunger 52 by means of a shouldered stud 62. The stud 62 has a reduced portion riveted through the front of the plunger 52, and a reduced shank at its rearward end projecting into a hole in the 25 staple-driver. Preferably, the staple-driver is provided with two holes for this purpose so that it may be reversed in position when its lower edge becomes worn.

The upper edge of the staple-driver 59 bears 30 against the underside of the hub 56 to take the thrust of the knob 55 when the plunger 52 is slid downwardly during the stapling operation. It will be understood that the staple-driver is slid 35 downwardly in the grooves 61 to cause its lower edge to impinge against the top of the forward staple fed off from the end of the arm 13 in the manner as shown in Fig. 7. It will be observed that the grooves 61 extend downwardly across 40 the front of the arm 13 so that when the leading 45 staple in the series feeds off from the end of the arm its legs will be held in the grooves bearing against the forward edges thereof. It is to be further observed that the legs of the forward staple are held frictionally in the grooves 61 by 50 the pressure of the following staples feeding from the rear until this foremost staple is carried downwardly by the descent of the driver 59.

The under side of the forward end of the arm 13 is cut away or recessed at 63 to receive a 55 staple-supporter 64, shown most clearly in Fig. 7. When the staple being driven slides downwardly beyond the control of the following staples it engages with the supporter 64 which holds it from dropping out of the grooves 61. The staple- 60 supporter 64 consists of a spade-shaped lever carried by a pivot pin 65 driven through the sides of the recess 63 in the arm 13. Normally, when the driver 59 is in raised position, the staple-supporter 64 is urged outwardly by the action 65 of a plunger 66 which slides in a bore 67 in the end of the arm 13, the plunger being forced outwardly by a coil spring 68 pocketed in the bore. The upper rearward side of the supporter 64 is flatted off at 69 to adapt it to strike against the 70 forward end of the arm 13 to limit its outward swinging action.

It will be understood that the knob 55 is depressed against the force of the spring 40 to slide the plunger 52 downwardly to actuate the 75 staple-driver 59, the reciprocal action of the

plunger being controlled by means which prevent the driver from being withdrawn or raised above the end of the arm 13 unless or until the staple being acted upon has been driven completely through the work. This means comprises an 5 automatically operated trip-latch 70 on the plunger 52 which is shown and described in detail in a prior application for U. S. Letters Patent, Serial No. 241,591, filed December 21, 1927.

The supporting frame 15 for the tag-strip roll 10 or spool comprises a pair of parallel sheet-metal arms, the inner ends of which are pivotally connected to the side-plates 16 of the base by a spacer-rod 80. The spacer-rod 80 is bored at its ends and threaded to receive the shanks of screws 15 81 passed through holes in the side-plates 16, see Figs. 5, 6, 7 and 8. The ends of the spacer-rod 80 bear against the side-arms of the frame 15 to frictionally hold the latter against the inner faces of the side-plates 16, this construction permitting 20 the frame 15 to be swung upwardly to fold across the top of the machine and to adjust it to operative position as illustrated in Fig. 1 of the drawings.

Intermediate their ends the arms of the frame 25 15 are provided with alined holes 82, in which are mounted the reduced ends of a spindle 84 adapted for insertion through the axial opening in the wooden core or spool 85 which holds the tag-strip roll 86. The outer ends of the arm of the frame 30 15 are connected by a thumb-screw 83 which may be removed for placing the roll in position to provide or replenish the supply of tags T. When the screw 83 is removed from the frame 15 the side-arms may be sprung apart sufficiently to withdraw the ends of the spindle 84 from the holes 82, thus permitting the empty spool 85 to be removed and a full spool inserted in its place.

The tag-strip T is fed forwardly to the stapling mechanism in the head 12 to position the foremost tag t beneath the driver 59 by means engaging the slits 87 disposed equidistantly along the length of the strip. The slits 87 terminate adjacent the edges of the strip T, that portion of the strip between each two adjacent slits constituting one tag, see Figs. 6 and 9, and the marginal portion of the strip connecting the tags at each end of the slit is adapted to be severed by means to be hereinafter described.

The tag-strip T is brought from the bottom of 50 the roll 86 into the rearward open end of the base 11 and then passed through a feed-chute constituted by a tube 88 disposed beneath the stapling-arm 13. The tube 88 is constructed from sheet-metal, folded to provide a flat top 89, relatively 55 narrow sides, and an open bottom comprising inward extensions or flanges 91. The bottom of the tube is disposed parallel with its top and spaced a suitable distance therefrom to provide an opening through which the strip of tags T may travel. The free edges of the flanges 91 are separated a 60 suitable distance to provide a relatively broad slot or gap extending lengthwise of the tube 88, the strip being supported by the flanges 91 on the bottom of the chute.

Depending from the bottom of the chute 88 are ears 92, preferably constructed in bifurcated form from folded sheet-metal strips and having their connecting portions welded, soldered or otherwise suitably secured to the flanges 91 at a point 65 intermediate the ends of the chute. An L-shaped bell-crank lever 94 is pivotally connected at its upper end to the ears 92 by means of a pin 95 projecting through alined openings therein as shown in Fig. 7. Through this connection the tube 88 is 70 75

adapted to be rocked or oscillated on the upper end of the lever 94 in the manner and for the purpose as later explained.

The bell-crank lever 94 is preferably formed 5 from sheet-metal with opposite parallel arms 93 connected by an integral cross-strip 96. Extending laterally from the lower ends of the arms 93 are shorter arms 97. The lever 94 is pivotally mounted on the base 11 by means of a bolt 98 10 passing through alined openings in its arms 93 and the side-plates 16, see Figs. 2, 3 and 7. Sleeves or bushings 99 are mounted on the bolt 98 between the sides of the lever 94 and the inner faces of the side-plates 16 to hold the lever from lateral 15 displacement with respect to the base 11, see also Fig. 6.

The bottom of the feed-chute 88 has a second pair of ears 100 depending from its forward end, these ears being secured to the bottom flanges 91 in the same manner as the ears 92. The ears 100 support the end of a strip-feeding pawl 101 which is pivotally mounted therebetween by means of a pin 102, see Fig. 7, with its forward end disposed in the gap between the flanges 91 of the chute 88. 25 The pawl 101 is preferably formed from sheet-metal with its outer end curled upwardly to form a finger or toe 103 adapted to engage the slits 87 in the strip of tags T and to pass through the strip and enter a slot 90 formed in the top 30 89 of the chute 88 near the forward end thereof. For operating the pawl 101 to carry its finger 103 into successive slits in the strip T, resilient means are provided in the form of a wire spring 104. The spring 104 is coiled around the pivot-pin 95 35 of the lever 94 with one arm 105 underlying the pawl 101 and its other arm 106 bearing against the cross-strip 96 of the lever. The tension of the spring 104 normally retains the finger 103 at the free end of the pawl engaged in the slot 40 90 in the top of the tube 88.

The forward end of the stapling-arm 13 carries a depending U-shaped bracket 107, preferably formed from sheet-metal and having its sides secured to the lower portion of the side-plates 36 45 of the head 12 by suitable means such as the screws 108, see Figs. 1 and 4. The bottom-plate 109 of the bracket 107 is spaced a suitable distance below the lower face of the arm 13 to provide a support for the strip of tags T as it is fed 50 forwardly from the chute 88, see Fig. 7. As shown in Figs. 2, 4 and 5, the tag-strip T is in most cases wider than the stapling-head 12, and therefore the bottom 109 of the bracket 107 is widened to accommodate the strip. To provide for this construction filler-plates 125, formed from rectangular pieces of sheet-metal, are inserted between the sides of the bracket 107 and the side-plates 36 of the head 12. The plates 125 are held in place by dowel-pins 126 and the screws 108 which fasten 55 the bracket to the head 12.

Fastened to the lower face of the arm 13 overlying the feed-chute or tube 88 is a plate 110 provided with a depending, inclined extension or arm 111, against which the forward end of the tube 88 is adapted to ride. The inclined extension 111 of the plate 110 terminates in a forward portion 112 disposed in parallel spaced relation with respect to the arm 13 and projecting into the space between the sides of the bracket 107, see Fig. 7.

70 A spring finger 113 projects from the forward end of the portion 112 of the arm 111, being secured thereto by a screw 114 or other suitable means. The tip of the finger 113 is curled downwardly to adapt it to engage the slits 87 in the tag-strip T, whereby it acts as a check-pawl to

prevent retrogressive movement of the strip.

The plate 110 has an ear 115 projecting from one side thereof and provided with a hole 116 through which extends the upper end of a rod 117, see Figs. 5, 6 and 7. The lower end of the rod 117 is pivotally connected at 118 to the forward end of the short arms 97 of the bell-crank lever 94, see also Fig. 1. A coil spring 119 encircles the rod 117 with its lower end bearing against a pin 120 projecting through the rod, while the upper 10 end of the spring bears against the lower face of the ear 115 on the plate 110. The upper end of the rod 117 carries a pin 121 which serves to prevent the rod from being withdrawn through the hole 116 in the ear 115 under force of the spring 15 119.

The function of the spring 119 is to actuate the bell-crank lever 94 when the arm 13 is depressed whereby to operate the feeding-mechanism to feed the tag-strip T forwardly. The forward 20 movement of the arms 93 of the lever 94 is limited by an adjustable stop which, as shown in Fig. 7, may comprise a screw 122 mounted in a flanged plate 123 fastened to the inner face of one of the side-plates 16 of the base 11, the screw being 25 locked in adjusted position by means of a check-nut 124 set up against the face of the plate.

The sides of the bracket 107 are provided with laterally projecting ears 127, see Figs. 1 and 4, disposed at the forward ends thereof and preferably 30 constructed integral therewith. Carried by the ears 127 are knives or cutters 129 pivotally mounted thereon by suitable means such as the bolts 128. The cutters 129 are disposed transversely of the arm 13 beneath the stapling-plunger 52 and their 35 free ends are normally maintained in raised position by a yoke-shaped leaf-spring 130 formed with upwardly bent ends as shown in Fig. 4. The spring 130 straddles the bottom of the bracket 107, being secured thereto by a screw 131 or other suitable 40 means. The upwardly-extending ends of the spring 130 bear against the rearward bottom edges of the cutters 129 to force them upwardly, the upward swinging movement of the cutters being limited by stop-lugs 132 projecting laterally from 45 the ears 127, see also Fig. 5. It will be observed by reference to Figs. 1, 2 and 4 that the lower portions of the side-plates 36 of the head 12 are cut away or notched at 133 to permit the tips of the cutters 129 to pass downwardly through the unslotted 50 marginal portions of the strip T to sever the tags therefrom.

The knives or cutters 129 are operated from the plunger 52 as it approaches the end of its downward stroke, the sides of the plunger carrying plates 134 formed with inturned bottom flanges 135 for engaging the rounded ends 136 of the cutters. The action of the cutters in severing the tags t from the strip T is hereinafter more fully explained in connection with the 60 operation of the complete machine.

To enhance the usefulness of machines falling within the scope of the present invention, means are provided for printing the sizes and prices of the goods or other indicia on the tags t as they 65 are affixed to the articles. One form of device for this purpose is herein shown as including a type-case 137 which is carried on a horizontal tongue 138 projecting forwardly from the plunger 52, being secured thereto by means of a screw 139. 70 The type-case 137 is preferably made in the form of a rectangular sheet-metal tube, the two opposite sides of which are extended upwardly in ears 141 and 142 folded one over the other to provide a slot 140 at the top of the case for the insertion 75

of the tongue 138. The screw 139 is threaded through the folded ears 141, 142 and screwed down against the tongue 138 to clamp the case in place. By loosening the screw 139 the case 5 137 may be removed to provide for setting the type therein. The tongue 138 on the plunger 12 may be formed by slitting the bottom portion of its front face vertically and then bending the cut-away strip of stock outwardly in the manner 10 shown in Fig. 7. In this way a recess 146 is formed in the bottom of the plunger 52 for receiving the rearward wall of the type-case 137, whereby the case is held firmly in place and prevented from turning on the screw 139.

15 A plurality of type units 143 may be mounted within the case 137 with "quads" or blanks employed when required to fill out the space. Clamping-plates 144 are arranged within the case 137 abutting two sides of the type and clamped 20 thereagainst by screws 145. When it is necessary to change the type the case 137 is removed from the head of the machine in the manner before described and the screws 145 loosened to release the pressure of the plates 144 against the type 143. 25 A pad 147 for inking the faces of the type 143 is mounted on the end of an arm 149 and secured thereto by a screw 148, see Figs. 2 to 4. The arm 149 is pivotally connected at 150 to a crank-arm 151 which is fast on the forward end of a rock-30 shaft 152 shown most clearly in Fig. 5. The arm 149 is loosely connected to the crank-arm 151 to permit movement thereof independently of the crank. The crank-arm 151 is provided with lugs 153 and 154 disposed on its opposite sides and 35 adapted to engage the arm 149 to control its swinging movement in the manner and for the purpose as later explained.

The rock-shaft 152 is journaled in ears 155 projecting laterally from a bracket 156 fastened 40 to the side of the plunger 52 as shown in Fig. 5. The end of the rock-shaft 152 opposite to the end carrying the crank-arm 151 is provided with a second crank 157 from which projects a crank-pin 158. The crank-pin 158 is adapted to ride 45 along the edge of a cam 159 which is rigidly supported from the base 11. As herein shown the cam 159 is formed on the upper end of the plate 123, hereinbefore referred to as carrying the stop-screw 122 for the bell-crank lever 94. The plate 50 123 is extended upwardly above the top of the base 11 and the cam 159 formed by bending over a portion of the metal as shown most clearly in Figs. 2 and 7.

The crank-pin 158 is held in engagement with the cam 159 by means of a spring 160 coiled around the rock-shaft 152. One end of the spring 160 is fixed to a pin 161 driven through the shaft 152 while its opposite end is extended to engage a lug 162 on the crank-arm 157. The form and location of the cam 159 is such as to cause it to release the crank-pin 158 when the stapling-head 12 is carried downwardly whereby the rock-shaft 152 is turned by the spring 160 to swing the arm 149 to carry the pad 147 away 60 from the face of the type 143. On the other hand, when the arm 13 is raised after the stapling operation the crank-pin 158 rides against the cam to rock the shaft 152 and lower the arm 149 to bring the pad against the type. The lug 65 154 operates the arm 149 to cause the removal of the pad from the faces of the type, while the opposite lug 153 serves as a stop to prevent the arm 149 from being accidentally swung upwardly. The method of operation of the complete machine is as next explained:

In Fig. 1 of the drawings the machine is illustrated with its base 11 resting on a suitable support and the stapling-arm 13 held raised under the action of the spring 32. The work W, which may comprise articles of wearing apparel or other objects to which a tag is to be affixed, is laid across the platen 14 in the manner shown in Fig. 7. With the arm 13 in raised position the bell-crank lever 94 carrying the strip-feeding chute 88 will be swung rearwardly under the action of the 10 connecting-rod 117, see Fig. 1, and the front end of the chute will be tilted upwardly under the force of the spring 104 to engage it with the plate 110 at the rear of the inclined arm 111 thereof.

15 After the work has been placed in position the operator presses against the knob 55 to first carry the arm 13 downwardly. As the arm 13 starts to swing downwardly the bell-crank lever 94 is swung forwardly on its pivot 98 by the pressure of the spring 119, thereby carrying the chute 88 20 forward with its end sliding on the inclined arm 111 of the plate 110. Continued downward movement of the arm 13 causes the chute 88 to be swung forwardly with its delivery end riding along the inclined arm 111 to finally bring it into the 25 position as illustrated in Fig. 7. This action of the chute 88 causes the feed-pawl 101 carried thereby to feed the tag-strip T forwardly a distance equal to the length of a single tag, it being understood that the extent of feed effected by 30 the chute is regulated in accordance with different requirements by the adjustment of the stop-screw 122. As the tag-strip is fed in this manner the slit 87 in advance of the one engaged by the pawl 101 comes into register with the 35 finger or check-pawl 113 and is engaged thereby to restrain the strip from retrogressive movement when the pawl 101 is carried back to engage a rearward slit in the strip after the completion of one operation of the machine. As illustrated in 40 Fig. 7 of the drawings, there will be two tags in advance of the finger 113, the foremost tag t overlying the work on the platen 14 and the slit between this tag and the next adjacent one disposed in alignment with the cutters 129. It should 45 be further noted that the tags t are fed forwardly in the manner above explained during the descent of the stapling-head 12 on the arm 13 to the platen, this action taking place prior to the depression of the stapling-plunger 52.

50 When the arm 13 is swung downwardly the bottom of the head 12 presses the tag t projecting from the front of the machine against the work W and clamps the latter against the platen 14. It will be understood that the spring 32 which 55 normally maintains the arm 13 in raised position has less force than the spring 40 under the presser-knob 55 so that the plunger 52 will not initially be forced down on the head 12. When, however, the bottom of the head has clamped the tag 60 and the work against the platen 14, then the continued pressure on knob 55 will slide the plunger 52 downwardly. As the plunger is slid downwardly on the head 12 the staple-driver 59 descends 65 against the foremost staple s in the series which has been pushed off from the arm 13, see Fig. 7; it having been explained that the staples are fed into operative position by the staple-pusher 45 which is urged forward on the bar 26 by its spring 44.

70 It should here be noted that the plunger 52 is controlled in its upward movement by the automatic action of the latch 70 in the manner as fully explained in the pending application for patent hereinbefore referred to. The purpose of 75

this control is to prevent the staple-device 59 from being raised above the end of the arm 13 to release a new staple until the first one fed into the grooves 61 has been driven out therefrom 5 and applied to the work. As the downward sliding movement of the plunger 52 is continued the staple-driver 59 forces the staple s down through the guideways 61 with the legs of the staple straddling the sides of the staple-supporter 64. At this 10 point the staple is held by the supporter 64 and in the normal operation of the device as the stroke of the staple-driver 59 is continued the staple will be driven into the work, puncturing the tag t and passing through the article therebeneath as the supporter 64 swings back out of the 15 way.

As the staple s is thus driven through the tag and the work the ends of its legs enter a groove 165 in the upper face of the platen 14 near the 20 rearward edge thereof. The bottom of this groove is formed in the manner as usual in machines of the present type to bend the legs of the staple inwardly and clinch them against the under side of the work.

25 As the plunger 52 reaches the end of its descent the face of the type 143 mounted in the case 137 is carried against the tag t to impress the appropriate legend or indicia thereon. The type faces are inked previous to this printing stroke 30 through the operation of the arm 149 carrying the pad 147. The arm 149 is operated from the rock-shaft 152 under the influence of the cam 159 during the upward movement of the stapling-arm 13 in the manner as later explained.

35 As the staple is being driven through the tag and the work in the manner above explained, the flanges 135 on the plates 134 on the sides of the plunger 52 engage the rounded ends of the cutters 129 as shown in Fig. 3 to force the cutters 40 downwardly against the tension of the spring 130. This action causes the cutters to sever the foremost tag from the strip at the slotted portion thereof, so that when pressure is removed from the knob 55 and the arm 13 is returned to its 45 normal raised position the work and the tag affixed thereto may be removed from the machine.

After the three operations of printing, affixing and severing the tag from the strip have been completed, the pressure on the knob 55 is released so that the plunger 52 will be slid upwardly 50 under the action of its spring 40. When the plunger is released the spring 32 comes into action to raise the arm 13 into the position shown in Fig. 1. During the upward movement of the arm 13 the strip-feeding means is returned to first 55 position as shown in Fig. 1 under the action of the rod 117 which rocks the bell-crank lever 94. It will be noted that the rearward motion of the lever 94 is effected positively through its connection 60 with the arm 13 to carry the pawl 101 back to engage a new notch in the tag-strip T. As the chute 88 is carried back by the bell-crank lever 94 the check-pawl 113 holds the tag-strip 65 from moving with it, while the feed pawl 101 is caused to rock against the tension of its spring 104 to release its toe or finger 103 from the slit 87 in the strip. The release of the pawl 101 is effected 70 automatically as the edge of the slit 87 rides up over the curved finger 103 to depress the pawl 75 against the light tension of its spring 104; the pawl being held depressed as its finger 103 rides on the under side of the strip until it registers with the next slit therein. At this juncture the spring 104 presses the pawl upwardly again to cause its finger 103 to enter through the register-

ing slit 87 in the tag-strip and the opening 90 in the top of the chute 88 to effect a firm grip on the tag-strip whereby it will be fed forward in the manner as previously explained at the next downward movement of the stapling-arm 13.

It is noted here that the forward movement of the bell-crank lever 94 is effected yieldingly through its connection with the arm 13. That is to say, when the arm 13 is swung downwardly it acts through the spring 119 to rock the lever 94 so that the forward movement of the feed-chute 88 may adjust itself to the required extent of feed. Stated briefly, the movement of the feed-chute is not in direct ratio to the movement of the arm 13, but is proportioned to feed the tag-strip T a distance corresponding exactly to the length of one tag as regulated by the stop-screw 122. This screw may be adjusted to allow the feed-chute to be moved forward to a greater or less extent in accordance with the 10 length of tags or various sizes or shapes, the spring connection between the arm 13 and the bell-crank lever 94 permitting lost motion between these parts in the proportion as required.

It has been stated that the raising of the 15 arm 13 causes the ink-pad 147 to be pressed against the type faces and this is accomplished in the manner as next explained. The spring 160 on the rock-shaft 152 tends to hold the crank-arm 151 at the forward end of the shaft 30 in the position illustrated in Figs. 2 and 3. With the crank-arm 151 in this relation the arm 149 carrying the ink-pad 147 is sustained in substantially horizontal position against the action 35 of gravity by the lug 154 on the crank-arm engaging its lower edge. As the stapling-arm 13 is raised under the action of its spring 32 the crank-pin 158 at the rearward end of the rock-shaft 152 is brought against the curved edge of the fixed cam 159 to cause it to slide therealong 40 as shown in Figs. 1 and 4. The inclined edge of the cam 159 is so formed as to cause the crank-pin 158 to rock the shaft 152 during this sliding engagement whereby to turn the crank-arm 151 to swing the arm 149 into the position illustrated 45 in Fig. 4. As the arm 149 is thus lowered into vertical position the ink-pad 147 is carried down into position beneath the face of the type 143 in the case 137. Now, as the turning movement 50 of the crank-arm is continued at the last end of the upward movement of the arm 13, it acts with a camming effect, due to the eccentric relation of the pivot 150 to its axis, to draw the arm 149 upwardly whereby to press the ink-pad 147 firmly against the type to apply the ink thereto. 55 Immediately the arm 13 is depressed again, however, the crank-pin 158 will ride off from the edge of the cam 159, as shown in Fig. 2, and its release allows the rock-shaft 152 to be rotated by its spring 160 to turn the crank-arm 151 whereby 60 to swing the arm 149 outwardly to remove the ink-pad 147 from the type.

It will be observed from the foregoing that the present invention provides a machine which is entirely automatic in its operation for printing, affixing and severing the tags from the strip to apply them to various articles such as apparel or other merchandise. The machine may be loaded to supply a large number of tags and the requisite number of staples for affixing them to the work, and may be operated at a high rate of speed by simply carrying the stapling-arm down against the work and pressing the plunger to print the tags and stitch them to the article to be labeled or price-marked. The improved 75

machine thus provides for economy of time and labor in tagging or price-marking practically all types of goods and supplies a need which to my knowledge has heretofore not been satisfied.

5 The mechanism of the machine is simple in construction, efficient in action and designed for economy in manufacture, while being particularly staunch and durable to avoid wear or getting out of order.

10 While I have herein shown and described the improved device as embodied in a preferred form of construction, it is to be understood that modifications may be made in the form and arrangement of its mechanism without departing from the spirit or scope of the invention. Therefore, without limiting myself in this respect, I claim:

1. In a stapling-machine, the combination of a work-support, means for feeding tags or the like into position to be stapled to the work held on the support, an arm movable with respect to the work-support, stapling-means carried on the arm and operative to insert the staples to attach the tags to the work, and printing-means operated from the stapling-means to print the tags as they are attached to the work.

2. In a stapling-machine, the combination of a work-support, means for feeding tags or the like into position to be stapled to the work held on the support, an arm movable with respect to the work-support, stapling-means carried on the arm and operative to insert the staples to attach the tags to the work, means actuated from the movement of the arm to operate the tag-feeding means, and printing-means carried on the arm and operated from the stapling-means to print the tags as they are attached to the work.

3. In a stapling-machine, the combination of a base, a work-support on the base, means for feeding tags or the like into position to be stapled to the work held on the support, an arm hinged to the base to adapt it to be moved down against the tag and work held on the support, stapling-means carried by said arm and operative to apply staples to attach the tags to the work, and printing-means carried by the stapling-means and operated therefrom to print the tags as they are attached to the work.

4. In a stapling-machine, the combination of a base, a work-support on the base, an arm hinged to the base to adapt it to be moved into position above the work-support, stapling-means carried by the arm, means for feeding tags or the like beneath the stapling-means, means actuated by the movement of the arm with respect to the work-support to actuate the tag-feeding means, and printing-means carried by the arm and operated by the stapling-means to print the tags as they are attached to the work.

5. In a stapling-machine, the combination of a base, a work-support on the base, an arm hinged to the base to adapt it to be moved against the work on the support, stapling-means carried by the arm, means for feeding a strip of tags or the like to position them above the work held on the support including a pawl engageable with the strip, oscillating-means for operating the feeding-means, and means connecting the arm to oscillate said operating-means during the opposite strokes of the arm.

6. In a stapling-machine, the combination of a work-support, an arm hinged to move toward and away from said support, stapling-means carried by the arm in position to operate on the work held on the support, means for feeding tags or the like beneath the stapling-means, means for oper-

ating the feeding-means, and resilient means yieldingly connecting the arm with the operating-means, said resilient means actuating the operating-means to feed a tag or the like during movement of the arm.

7. In a stapling-machine, the combination of a work-support, an arm hinged to swing with respect to the support, stapling-means carried by the arm, means for raising the arm away from the support, means for feeding tags or the like beneath the stapling-means, a lever for operating the feeding-means, a link connecting the lever to the stapling-arm to positively actuate the feeding-means when the arm is raised, and resilient means connecting the arm to operate the lever to actuate the feeding-means when the arm is depressed prior to the stapling operation.

8. In a stapling-machine, the combination of a work-support, stapling-means for operating on the work held on the support, and means for feeding tags or the like to the stapling-means comprising a chute for receiving a perforated strip of tags, a pawl for engaging the perforations in the tag-strip, means for moving the chute to feed the tags to the stapling-means, and means for retracting the chute to engage the feed-pawl with the successive perforations in the strip.

9. In a stapling-machine, the combination with the stapling-means, of means for feeding tags or the like to the stapling-means comprising a chute for receiving a perforated strip of tags, a rockable pawl on the chute adapted to engage the perforations in the tag-strip, means for moving the chute forwardly to feed the tags to the stapling-means, means for retracting the chute to cause the feed-pawl to engage a new perforation in the strip, and means for holding the strip to prevent retrogressive movement thereof.

10. In a stapling-machine, the combination with the stapling-means, of means for feeding tags or the like thereto comprising a chute through which the perforated strip of tags passes, a pawl engaging the perforations in the strip passing through the chute, a lever for oscillating the feed-chute, means for actuating said lever to move the chute rearwardly to withdraw its pawl from one perforation in the strip and engage it with a succeeding perforation, means for holding the tag-strip from retrogressive movement, and means operative to move the feed-chute forwardly to feed a fresh tag into position with respect to the stapling-means.

11. In a stapling-machine, the combination of a work-support, reciprocable means for feeding a strip of tags or the like to successively present them to the work held on the support, a movable stapling-arm, stapling-means on the arm for affixing the tags to the work, means actuated by the movement of the stapling-arm to reciprocate the tag-feeding means, and means actuated during the operation of the stapling-means to sever the foremost tag from the strip as it is stapled to the work.

12. In a stapling-machine, the combination of a work-support, a movable stapling-arm, a stapling-head on the arm, a stapling-means carried by the head, reciprocable means for feeding a strip of tags or the like to successively present them to the work held on the support, means actuated by the movement of the stapling-arm to reciprocate the tag-feeding means, cutting-means carried by the head, and means for actuating the cutting-means during the operation of the stapling-means to sever the foremost tag from the strip as it is affixed to the work.

13. In a stapling-machine, the combination of a work-support, a stapling-arm movable with respect to the work-support, means for feeding tags or the like to the work held on the support, 5 stapling-means on the arm for attaching the tags to the work, and means carried by the arm and operated by the stapling-means for printing the tags as they are attached to the work.
14. In a stapling-machine, the combination of 10 a movable stapling-arm, a stapling-head on the arm, stapling-means reciprocable on the head, means for feeding tags or the like to the stapling-means, and means carried by the stapling-means and reciprocable therewith to print the tags as 15 they are stapled to the work.
15. In a stapling-machine, the combination of a work-support, means for feeding tags or the like into position above the work held on the support, a stapling-arm movable with respect to said support, staple-driving means on the arm for applying the staples to affix the tags to the work, a plunger for operating the staple-driving means, type-holding means carried by the plunger for printing the tags as they are stapled to the work, 20 and inking-means operated by the upward movement of the arm to ink the type after each printing operation.
16. In a device of the type specified, the combination of stapling-means, means for feeding a strip of tags or the like relative to the stapling-means, a pair of knives at the sides of the 25 stapling-means, and means for actuating the knives during the stapling operation to cause them to sever the edges of the tag-strip.
17. In a device of the type specified, the combination of a work-support, means for feeding a strip of perforated tags to successively position the individual tags above the work held on the support, stapling-means for applying staples to attach the tags to the work, and a knife at either side of the work-support operated from the 30 stapling-means to sever the edges of the tag to detach it from the strip.
18. In a device of the type specified, the combination of a work-support, means for feeding a perforated strip of tags across the work-support, 15 stapling-means above the work-support, knives pivoted at the sides of the stapling-means, a plunger for operating the stapling-means to staple the tags to the work, and means operated from the plunger to actuate the knives to sever the edges of the strip to detach the tags therefrom. 20
19. In a device of the type specified, the combination of a work-support, means for feeding a perforated strip of tags across the work-support, 25 stapling-means above the work-support, a plunger for actuating the stapling-means, a pair of knives pivoted at the opposite sides of the stapling-means, resilient-means for normally maintaining the knives in elevated position, and means on the plunger for moving the knives downward to cause them to sever the edges of 30 the strip to detach the tags therefrom.

ALBERT F. HORTON.
